(57) **CLAIM**

The ornamental design for a feeding bottle for infants as shown and described.

DESCRIPTION

FIG. 1 is a front elevational view of a feeding bottle for infants showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a bottom, rear and left side perspective view thereof;

FIG. 9 is a top, front and right side perspective view showing the feeding bottle for infants in a use state; and,

FIG. 10 is an enlarged view of portion 10 in FIG. 8.

The broken lines in the drawings illustrate portions of the feeding bottle for infants which form no part of the claimed design.

The dot-dash broken lines represent the enlarged boundaries in FIGS. 8 & 10 and forms no part of the claimed design.

1 Claim, 9 Drawing Sheets
